DESIGN FOR A BOAT

Paul G. Larson, Little Falls, Minn.

Application November 12, 1940, Serial No. 96,465

Term of patent 14 years

To all whom it may concern:

Be it known that I, Paul G. Larson, a citizen of the United States, residing at Little Falls, in the county of Morrison and State of Minnesota, have invented a new, original, and ornamental Design for Boats, of which the following is a specification, reference being had to the accompanying drawing, forming part thereof, and in which—

Figure 1 is a perspective view of a boat, showing my new design;

Figure 2 is a side elevational view of Figure 1;
Figure 3 is a front elevational view of the boat;
and

Figure 4 is a rear view of the boat with the rudder and propeller omitted.

The characteristic features of my design reside in the portions shown in full lines.

I claim:

The ornamental design for a boat, substantially as shown and described.

PAUL G. LARSON.
